KILN FOR THE MANUFACTURE OF BLOATED CLAY PRODUCTS

Filed Oct. 26, 1929

UNITED STATES PATENT OFFICE

EDWIN M. WYATT, OF CLEVELAND, OHIO, ASSIGNOR, BY MESNE ASSIGNMENTS, TO
AMERICAN FACE BRICK RESEARCH CORPORATION, A CORPORATION OF ILLINOIS

KILN FOR THE MANUFACTURE OF BLOATED CLAY PRODUCTS

Application filed October 26, 1929. Serial No. 402,601.

This invention relates to improvements in kilns for the manufacture of bloated clay products.

The kiln of the present invention is designed especially for use in the production of building units composed of bloated clay or other argillaceous material as set forth and described in co-pending application Serial No. 383,358, filed July 31, 1929, Cellular building material.

In the production of such a product, it is necessary to feed the raw material, in granular form, to a heat zone maintained at a temperature sufficient to first cause the searing over of the layer of material, and thereafter to cause a bloating of the mass due to the evolution of gases, with the result that the bloated material possesses a cellular structure caused by the expansion of gases within the fused and plastic mass.

In the commercial production of such material, it is desirable to provide means for continuously feeding granular raw material into the kiln in the form of a uniform layer, which under heat treatment will coalesce and expand into the form of a continuous column of bloated material, which is transported through the heat zone and through an annealing chamber, and finally delivered to saws or other cutting devices which sever the continuous slab or column into units of the desired dimensions.

In the kiln of the present invention, provision is made for feeding the raw material to a traveling conveyor, which in effect constitutes the floor of the bloating chamber, and which of necessity must be formed of refractory material in order to withstand the high temperatures required, which ordinarily range from 2000 to 2300° F. within the bloating chamber.

Provision is also made for initially leveling off the granular material to provide a layer of uniform thickness, and for rolling down or otherwise uniformly configuring the surface of the bloated slab of material while in the soft or plastic state, to maintain uniformity in thickness of the completed slab, or other desired configuration.

Other objects and details will appear

from a description of the invention, in conjunction with the accompanying drawing, wherein,

Figure 1 is a longitudinal sectional view in diagrammatic form of a kiln embodying the features of the present invention; and

Fig. 2 is a similar view illustrating a modification of the same.

Referring to Figure 1, the kiln is built to provide a bloating chamber 10 having a top wall or roof 11 and a forward wall 12, the lower edge of which constitutes a cut off for leveling down the layer of argillaceous material which is fed from a hopper 13 to the lower edge of the wall 12.

The floor of the bloating chamber is afforded by slabs 14 of refractory material, each slab being carried by a truck 15 provided with wheels 16 which travel upon a track 17. The slabs thus constitute the deck plates of the respective trucks, and when the trucks are coupled together in train formation present a continuous floor or surface for the deposit of the material.

The trucks are closely spaced to bring the slabs 14 into contacting relation, so that they constitute in effect a continuous movable floor which travels at a slow speed through the kiln.

The kiln also embodies a chamber 18 constituting an annealing oven, which is separated from the bloating chamber by a partition 19, the lower edge of which is sufficiently elevated above the traveling floor to permit the passage thereunder of the bloated slab or column 20, but without affording free communication between the bloating chamber and the annealing oven. As shown in Fig. 1, the central portion of the annealing oven is broken away, but this oven should be of sufficient length, in relation to the speed of movement of the traveling conveyor, to afford time for the slow cooling of the product in order to toughen the same and avoid fracture due to rapid cooling.

In order to prevent the argillaceous material, when fused and sticky, from adhering to the surface of the traveling conveyor, a layer of sand or other parting material is deposited upon the floor at a point in advance

of the discharge end of the hopper 13, which sand or other parting material is fed from a hopper 21 located immediately adjacent to the hopper 13.

5. In order to more perfectly level down the top and sides of the bloated material, a top roller 22 and side rollers 23 may be provided, which act against the upper surface and side edges of the column respectively. It is preferred to employ rollers of refractory material which may if desired be cooled by the passage of water or other liquids or gases, although the use of such rollers may be dispensed with where it is desired to retain the somewhat rough and pebbled natural surface texture of the bloated column, or where for other reasons exact uniformity in dimensions is not required.

As shown, the rollers are located near the forward end of the annealing oven, where they will be somewhat protected from the intense heat within the bloating chamber, and where they will act upon the top surface and edges of the bloated column while still in a somewhat soft or plastic condition, although if desired such rollers or other adequate means may be located within the bloating chamber itself.

Where the rollers are maintained in a relatively cool state by the passage of cool liquid or gases, it will ordinarily not be necessary to otherwise provide against adherence of the bloated material, but in case a tendency to adhere is encountered it may be overcome by the feeding of a thin layer of sand or other parting material upon the surface of the bloated slab in advance of the line of contact of the roller or rollers. As shown, such sand or the like may be fed from a hopper 24, which serves to illustrate the principle involved.

The annealing oven at its rear end terminates in an end wall 25, under which the completed column advances to one or more longitudinal cutting wheels 26 and cross cutting wheels 27, which serve to divide the completed column into bricklike units of the desired dimensions.

As shown, the kiln of the present invention is associated with an inclined rotary kiln 28 of a well known type of construction, which serves to preheat the granular material under agitation and discharge it, while still in granular form, into the hopper 13, although it is not essential in all cases in the practice of the present invention that the material be preheated.

The trucks, constituting the movable conveyor of the kiln, after they have completed the transport of the column of the cutting wheels, may be unloaded and returned to the starting point, either individually or in continuous train formation, the track being properly configured to permit of the desired manipulation.

From an inspection of Fig. 1, it will be observed that the material, while in granular form, is leveled down to a layer of the desired depth, and that as the layer progresses through the bloating chamber it will become expanded to two or more times the original depth, the particles coalescing together into a continuous slab before the column emerges from the bloating chamber into the annealing oven.

The speed of movement of the cars or trucks constituting the movable floor will be regulated to afford adequate time for the column to be fully bloated within the bloating chamber, but without affording additional time which might result in an excessive liquefaction of the material and a breaking down of the cellular structure. The arrangement is one which permits the feeding speed to be regulated in such a way as to bring the material to the desired condition within the bloating chamber and to then introduce it to the cooler atmosphere within the annealing oven, so that it will become adequately annealed during the period allowed for its transport through the annealing oven, and finally reach the cutting wheels in a cooled and toughened condition.

The modification shown in Fig. 2 is quite similar in principle, although differing somewhat in detail. In this case, the kiln is provided with a charging chamber 28, a bloating chamber 29, a rolling chamber 30, and an annealing chamber or oven 31. A strike off wall 32 separates the charging chamber from the bloating chamber, and partition walls 33 and 34 divide the rolling chamber from the bloating chamber and the annealing chamber respectively. The annealing chamber terminates in an end wall 35.

The material is fed down through a hopper 36 immediately in advance of the strike off wall 32, which serves to level down the layer of material in the manner heretofore described. Sand or other parting material is discharged from a hopper 37 immediately in advance of the hopper 36. In this instance, the material is shown as fed from a chute 38 into the hopper 36, although obviously it might be fed from a preheater, rotary or otherwise, as heretofore described.

The material is fed onto an endless plate conveyor 39 composed of slabs 40 of refractory material, the ends of which preferably extend through the sides of the kiln to exteriorly positioned chains 41 composed of metallic links, which pass over exteriorly positioned sprocket wheels 42 driven at a slow speed from any suitable source of power. By linking the refractory plates onto exteriorly positioned chains in the manner indicated, the links will be relieved from the extreme heat within the interior of the kiln.

As the bloated column leaves the endless plate conveyor, it will pass over and be sup-

ported upon a transfer slide 43 in the form of a hollow shoe, which may be water cooled or otherwise cooled to prevent adherence of the slab or column of material. As the material enters the annealing chamber, it passes upon the upper turn of an endless metal conveyor 44 carried over rollers 45. Since the temperature in the annealing chamber is much lower than that in the bloating chamber, it is feasible to use a metal conveyor at this stage of the operation. After passing through the annealing chamber, the slab or column of material emerges and passes onto a stationary table 46, where it is severed by cutting wheels into units of the desired size.

The material, as it passes from the bloating chamber into the rolling chamber is acted upon by a top roller 47 and side rollers 48 similar to those heretofore described.

In the case of the plate conveyor shown in Fig. 2, the refractory plates constituting the conveyor surface are completely enclosed within the structure of the kiln, which is desirable in order to conserve heat and also to relieve the plates from the deteriorating effect due to frequent and violent changes in temperature.

Furthermore, the structure of Fig. 2 shows the provision of a rolling chamber which lies intermediate the bloating chamber and the annealing chamber, and serves to some extent to afford a zone of intermediate temperature, through which the material passes before it enters the relatively cool atmosphere of the annealing chamber. However, it is obvious that the kiln in the form shown in Fig. 1 might be similarly provided with an intermediate chamber by simply adding a partition wall in all respects similar to the wall of Fig. 2.

It will be obvious that the particular arrangement chosen will depend somewhat upon local conditions and the technique to be observed in the performance of the process.

Where it is desired to provide means for transporting the completed blocks from the furnace to a somewhat distant point, the truck or car arrangement shown in Fig. 1 may be deemed preferable, since the individual trucks, after passing the cutting wheels, may be employed individually for transporting the completed blocks to the desired point. However, in doing so, the tops, or deck slabs, of refractory material would become cooled to a low temperature, so that heat is not conserved to the same degree as in the construction of Fig. 2, in which the endless conveyor is continuously enclosed.

Numerous variations in detail may be introduced without departing from the spirit of the invention, which essentially comprises the employment of a continuously moving conveyor for transporting the material

through the various portions of the furnace to the point of delivery.

I claim:

1. In a kiln of the class described, the combination of a bloating chamber, a chute for delivering granular earthy material at one end of the bloating chamber, a movable conveyor for receiving said material in the form of a continuous layer and transporting the same through the bloating chamber, and roller means for acting upon the surface of the material after bloating. 75

2. In a kiln of the class described, the combination of a bloating chamber, a chute for delivering granular earthy material at one end of the bloating chamber, a movable conveyor for receiving said material in the form of a continuous layer and transporting the same through the bloating chamber, a strike off wall located in proximate relation to the chute and above the conveyor for leveling the material on the conveyor to the desired depth, and roller means for acting upon the surface of the material after bloating. 80 85

3. In a kiln of the class described, the combination of a bloating chamber, a chute for delivering granular earthy material at one end of the bloating chamber, a movable conveyor for receiving said material in the form of a continuous layer and transporting the same through the bloating chamber, a chute located in advance of the first named chute for delivering parting material onto the surface of the conveyor to prevent adhesion of the granular material, and roller means for acting upon the surface of the material after bloating. 90 95 100

4. In a kiln of the class described, the combination of a bloating chamber, a chute for delivering granular earthy material at one end of the bloating chamber, a movable conveyor for receiving said material in the form of a continuous layer and transporting the same through the bloating chamber, a strike off wall located in proximate relation to the chute and above the conveyor for leveling the material on the conveyor to the desired depth, a chute located in advance of the first named chute for delivering parting material onto the surface of the conveyor to prevent adhesion of the granular material, and roller means for acting upon the surface of the material after bloating. 105 110 115

5. In a kiln of the class described, the combination of an enclosed bloating chamber and an enclosed annealing chamber, conveyor means furnishing a surface movable from a position outside of and into and through the bloating chamber and through the annealing chamber, means for delivering a continuous layer of granular earthy material to the conveyor prior to its entry into the bloating chamber, and means for delivering a parting material to the surface of the conveyor 120 125 130

veyor prior to the deposit thereon of the granular material.

6. In a kiln of the class described, the combination of a bloating chamber and an annealing chamber, conveyor means furnishing a surface movable through the bloating chamber and through the annealing chamber, means for delivering a continuous layer of granular earthy material to the conveyor prior to its entry into the bloating chamber, and cutting devices in proximate relation to the conveyor means and located beyond the annealing chamber for severing the material into units of the desired dimensions.

7. In a kiln of the class described, the combination of a bloating chamber and an annealing chamber, conveyor means furnishing a surface movable through the bloating chamber and through the annealing chamber, means for delivering a continuous layer of granular earthy material to the conveyor prior to its entry into the bloating chamber, means for delivering parting material to the surface of the conveyor prior to the deposit thereon of the granular material, and cutting devices in proximate relation to the conveyor means and located beyond the annealing chamber for severing the material into units of the desired dimensions.

8. In a kiln of the class described, the combination of a bloating chamber and an annealing chamber, a movable conveyor operable through the bloating chamber and provided with surface slabs of refractory material, and means for delivering a continuous layer of granular earthy material to the surface of the conveyor in advance of its entry into the bloating chamber.

9. In a kiln of the class described, the combination of a bloating chamber and an annealing chamber, a movable conveyor operable through the bloating chamber and provided with surface slabs of refractory material, means for delivering a continuous layer of granular earthy material to the surface of the conveyor in advance of its entry into the bloating chamber, and means for delivering parting material to the surface of the conveyor in advance of the deposit thereon of the granular material.

10. In a kiln of the class described, the combination of a bloating chamber and an annealing chamber, a movable conveyor operable through the bloating chamber and provided with surface slabs of refractory material, means for delivering a continuous layer of granular earthy material to the surface of the conveyor in advance of its entry into the bloating chamber, and cutting devices located beyond the annealing chamber and adapted to sever the material into units of the desired dimensions.

11. In a kiln of the class described, the combination of a bloating chamber and an annealing chamber, a movable conveyor op-

erable through the bloating chamber and provided with surface slabs of refractory material, means for delivering a continuous layer of granular earthy material to the surface of the conveyor in advance of its entry into the bloating chamber, means for delivering parting material to the surface of the conveyor in advance of the deposit thereon of the granular material, and cutting devices located beyond the annealing chamber and adapted to sever the material into units of the desired dimensions.

12. In a kiln of the class described, the combination of a bloating chamber and an annealing chamber, a series of movable trucks provided with deck plates of refractory material and mounted to move through the bloating chamber and through the annealing chamber in continuous procession, and means for delivering granular earthy material to the surface presented by the deck plates prior to the transport of such material into the bloating chamber.

13. In a kiln of the class described, the combination of a bloating chamber and an annealing chamber, a series of movable trucks provided with deck plates of refractory material and mounted to move through the bloating chamber and through the annealing chamber in continuous procession, means for delivering granular earthy material to the surface presented by the deck plates prior to the transport of such material into the bloating chamber, and means for delivering parting material to the surface of such deck plates prior to the deposit thereon of the granular material.

14. In a kiln of the class described, the combination of a bloating chamber and an annealing chamber, a series of movable trucks provided with deck plates of refractory material and mounted to move through the bloating chamber and through the annealing chamber in continuous procession, means for delivering granular earthy material to the surface presented by the deck plates prior to the transport of such material into the bloating chamber, and cutting devices located beyond the annealing chamber and adapted to cut the material transported upon the deck plates into units of the desired dimensions.

15. In a kiln of the class described, the combination of a bloating chamber and an annealing chamber, a series of movable trucks provided with deck plates of refractory material and mounted to move through the bloating chamber and through the annealing chamber in continuous procession, means for delivering granular earthy material to the surface presented by the deck plates prior to the transport of such material into the bloating chamber, means for delivering parting material to the surface of such deck plates prior to the deposit

thereon of the granular material, and cutting devices located beyond the annealing chamber and adapted to cut the material transported upon the deck plates into units of the desired dimensions.

5. 16. In a kiln of the class described, the combination of an enclosed bloating chamber and an enclosed annealing chamber located in progressive alignment with one another, conveyor means furnishing a surface movable from a position outside of and into and through the bloating chamber and through the annealing chamber, and means for delivering a continuous layer of granular 10 earthy material to the conveyor prior to its entry into the bloating chamber.

17. In a kiln of the class described, the combination of a bloating chamber, a chute for delivering granular earthy material at 20 one end of the bloating chamber, a movable conveyor for receiving said material in the form of a continuous layer and transporting the same through the bloating chamber, and leveling means for smoothing down the surface of the material after bloating.

25. 18. In a kiln of the class described, the combination of a bloating chamber, a chute for delivering granular earthy material at one end of the bloating chamber, a movable conveyor for receiving said material in the form of a continuous layer and transporting the same through the bloating chamber, a strike off wall located in proximate relation to the chute and above the conveyor for 30 leveling the material on the conveyor to the desired depth, and leveling means for smoothing down the surface of the material after bloating.

35. 19. In a kiln of the class described, the combination of a bloating chamber, a chute for delivering granular earthy material at one end of the bloating chamber, a movable conveyor for receiving said material in the form of a continuous layer and transporting the same through the bloating chamber, a chute located in advance of the first named chute for delivering parting material onto the surface of the conveyor to prevent adherence of the granular material, and leveling 40 means for smoothing down the surface of the material after bloating.

45. In witness that I claim the foregoing I have hereunto subscribed my name this 16th day of October, 1929.

50. EDWIN M. WYATT.
